UNITED STATES PATENT OFFICE.

HERBERT T. JENKINS, OF PORTSMOUTH, NEW HAMPSHIRE, ASSIGNOR TO MORLEY
BUTTON MANUFACTURING COMPANY, OF PORTSMOUTH, NEW HAMPSHIRE, A COR-
PORATION OF MAINE.

BUTTON.

Application filed October 29, 1923. Serial No. 671,299.

To all whom it may concern:

Be it known that I, HERBERT T. JENKINS, a citizen of the United States, residing at Portsmouth, in the county of Rockingham 5 and State of New Hampshire, have invented new and useful Improvements in Buttons, of which the following is a specification.

This invention relates to buttons and more particularly to that class of buttons used on 10 shoes, gaiters, etc. and which ordinarily comprise a metal eye embedded in a head of hardened plastic material such as papier-mâché and similar compositions.

The invention is an improvement on the 15 button for which U. S. Letters Patent were issued to Fred Oldfield on December 29th, 1908, No. 907,865, "button," the object of the invention being to more securely anchor the eye in the head of the button, and particularly the object of the invention is to securely 20 lock the peg, which assists in holding the loop in the button head, without splitting the head.

It has been found that by the use of a peg 25 constructed in accordance with this invention the percentage of split button heads is very materially reduced, in fact such percentage is rendered almost negligible. This result is attained and the gist of the invention resides in providing the shank of the 30 peg with one or more locking members, preferably elongated and inclined at an angle to the longitudinal median plane of the peg. These inclined projections are furthermore 35 preferably provided with tapered ends and are spaced apart from the upper end of the shank and also may be spaced apart from both ends of the shank.

The invention consists of a button such as 40 hereinafter described and particularly as pointed out in the claims.

Referring to the drawings:

Figure 1 is a plan view of my improved button.

Fig. 2 is a front elevation of the same.

Fig. 3 is a sectional elevation taken on the line 3—3 of Fig. 1.

Fig. 4 is a detail front elevation of the loop or eye.

Fig. 5 is a front elevation of a peg on a very much enlarged scale.

Fig. 6 is a rear elevation of the peg illustrated in Fig. 5.

Fig. 7 is a sectional plan taken on the line 55 7—7, Fig. 5.

Fig. 8 is a detail section taken on the line 8—8 of Fig. 5.

Like numerals refer to like parts throughout the several views of the drawings.

In the drawings, 10 is the button head 60 which in practice is preferably formed of hardened plastic material such as papier-mâché. 11 is the loop, the ends of which are bevelled as at 12. 13 is a peg consisting of a head 14 and a shank 15. The shank 15 is 65 provided with a pair of diametrically opposed locking members 16 and 17. Each of these members is inclined at an angle to the longitudinal median plane of the peg and in their preferred form are tapered at opposite 70 ends and also are tapered from the central portion inwardly toward the shank, thus forming oval shaped wedges. Each of the locking members 16 and 17 are spaced apart from the upper end of the shank 15 and 75 preferably are spaced apart from the lower end of said shank. One of the locking members 16 is positioned with its upper end further removed from the under side of the head 14 than is the upper end of the other 80 locking member 17.

The button is manufactured in the manner well known to those skilled in the art whereby the ends of the loop or eye 11 are driven into the head of the button and when 85 so driven, due to the inclined ends thereof, they spread apart and clinch in said head as illustrated in Fig. 3. Simultaneously with this driving of the ends of the loop into the head of the button, a hole 18 is formed in 90 the button head extending downwardly from the top thereof. The shank 15 of the peg 13 is then driven into the hole 18 and during this driving operation the inclined locking 95 projections 16 and 17 are driven into the head in such a manner that when the peg has been completely driven into the head, there is a portion of the button head located between the upper ends of each of the locking members 16 and 17 and the lower side of the 100 head 14 thus preventing the peg from being withdrawn, and also by this construction it is unnecessary to have the shank of the peg such a tight fit in the hole 18 as would be the case if the locking projections were not provided. Thus the peg is firmly locked in the button head without splitting the same. The lower ends of the locking members 16 and 17 are preferably spaced apart from the lower 105 end of the shank, thus allowing the shank to 110

enter the hole and center the same in the button head before the locking projections begin to be forced into the button head.

It will be noted that the outer edge of the 5 locking members is inclined toward the opposite ends of said locking members as well as the sides thereof, as illustrated in Fig. 8. Thus the forcing apart of the material to allow the locking projections to enter the 10 same is gradual.

The shape and location of the locking members contributes to the successful insertion of the peg without splitting the button, and also contributes to the firmness of the 15 location within the button and obviates the necessity of a very tight fit of the peg in the hole which receives it.

It is evident that without departing from the spirit of my invention that a single locking 20 member may be employed instead of a pair of locking members as hereinbefore described and as shown in the drawings, and some of the claims are drawn with this construction in view.

25 I claim:

1. A button comprising a one-part head of hardened plastic material, an eye formed of a loop of metal having its ends imbedded in the material of the head, a peg driven 30 into the material of said head between the ends of the loop and a locking member on the shank of said peg imbedded in the material of the head.

2. A button comprising a one-part head 35 of hardened plastic material, an eye formed of a loop of metal having its ends imbedded in the material of the head, a peg driven into the material of said head between the ends of the loop and an elongated locking 40 member on the shank of said peg imbedded in the material of the head and inclined at an angle to the longitudinal median plane thereof.

3. A button comprising a one-part head 45 of hardened plastic material, an eye formed of a loop of metal having its ends imbedded in the material of the head, a peg driven into the material of said head between the ends of the loop, an elongated locking mem-

ber on the shank of said peg imbedded in 50 the material of the head and inclined at an angle to the longitudinal median plane thereof and with tapered ends.

4. A button comprising a one-part head of hardened plastic material, an eye formed 55 of a loop of metal having its ends imbedded in the material of the head, a peg driven into the material of said head between the ends of the loop and a locking member on the shank of said peg spaced apart from 60 the upper end of said shank and imbedded in the material of the head.

5. A button comprising a one-part head of hardened plastic material, an eye formed 65 of a loop of metal having its ends imbedded in the material of the head, a peg driven into the material of said head between the ends of the loop and a locking member on the shank of said peg spaced apart from 70 both ends of said shank and imbedded in the material of the head.

6. A button comprising a one-part head of hardened plastic material, an eye formed 75 of a loop of metal having its ends imbedded in the material of the head, a peg driven into the material of said head between the ends of the loop and a plurality of locking members spaced apart on the shank of said peg and imbedded in the material of the 80 head.

7. A button comprising a one-part head of hardened plastic material, an eye formed 85 of a loop of metal having its ends imbedded in the material of the head, a peg driven into the material of said head between the ends of the loop and a pair of diametrically opposed locking members on said shank inclined at an angle to the longitudinal median plane thereof and inclined in opposite 90 directions thereto and imbedded in the material of the head.

In testimony whereof I have hereunto set my hand in presence of two subscribing witnesses.

HERBERT T. JENKINS.
